Primary Examiner — Omeed Agilee*Assistant Examiner* — David Truong(74) *Attorney, Agent, or Firm* — Dunlap Bennett & Ludwig, PLLC; Anna L. Kinney(57) **CLAIM**

The ornamental design for an insert for smoking products, as shown and described.

DESCRIPTION

FIG. 1 is a front, top, right perspective view of an insert for smoking products, showing my new design, with the rear, top, right perspective view being a mirror image thereof; FIG. 2 is another front, top, right perspective view thereof, shown in use;

FIG. 3 is a top plan view thereof;

FIG. 4 is a bottom plan view thereof;

FIG. 5 is a front view thereof;

FIG. 6 is a rear view thereof;

FIG. 7 is a right side view thereof; and,

FIG. 8 is a left side view thereof.

The broken lines shown in FIG. 2 depict environmental subject matter and forms no part of the claimed design.

1 Claim, 4 Drawing Sheets(56)
